UNITED STATES PATENT OFFICE

WILLIAM R. TALIAFERRO, OF PITTSBURGH, PENNSYLVANIA, ASSIGNOR TO WESTINGHOUSE ELECTRIC & MANUFACTURING COMPANY, A CORPORATION OF PENNSYLVANIA

METAL ARC BOX FOR FUSES

Application filed August 22, 1928. Serial No. 301,250.

My invention relates to arc chutes or boxes and more particularly to an arc box for an expulsion type fuse.

One object of my invention is to provide 5 a closure member for the end of an expulsion fuse that shall prevent the flame or the expelled portions of the fuse from passing out of the structure.

Another object of my invention is to provide 10 an arc box of the above-described type that shall be constructed entirely of metal except for the insulating portions employed to mount the fuse structure within the closure member.

Difficulty has often been experienced in 15 employing the expulsion type fuse due to the ejecting of portions of the fuse structure and the hot metals upon adjacent circuits or apparatus causing short circuits or 20 other damage. Difficulty has also been experienced because of gases being propelled along the outer surface of the fuse forming an ionized path causing the arc to restrike between the terminals thereof or in a grounded system, between ground and the line terminal.

My invention overcomes these objectionable features of the expulsion type fuse by 25 providing the expulsion end thereof with an arc box of such form as to prevent ejected gases from ionizing the space between the terminals of the fuse.

My invention will best be understood from 30 the following description having reference to the accompanying drawings, in which:

Figure 1 is a diagrammatic view of a circuit connected to an expulsion fuse embodying the features of my invention shown in 35 section; and,

Fig. 2 is an end view thereof in elevation.

My invention comprises, in general, an expulsion type fuse 1 that has one end within the arc box 2 and supported therein by a partition 3 that prevents the escape of gas and

the formation of an ionized path between the terminals of the fuse 1.

The expulsion fuse 1 is of the conventional type having its expulsion end, from which the fuse element 4 extends, located within the box 2. Within the outer casing of the expulsion fuse 1, a secondary tube containing a metal portion (not shown) is located and is employed to assure overload operation of the fuse structure.

The arc box 2 is constructed of metal to increase the life and strength thereof and at the same time to reduce its cost. The end 50 3 adjacent the fuse 1, is formed of insulation and has a line terminal 5 and a fuse terminal 6 mounted thereon by the bolt 7. The opposite end is covered by a wire gauze 8 to permit the escape of the evolved gases and to deionize the flame that may be projected therethrough.

A portion 9 of the top of the arc box 2 is hingedly attached thereto by hinges 10 and is employed as a means of ingress to the box in order to adjust or renew the fuse element 4. The metal box 2 is grounded by means of 60 a ground wire 11 that is attached thereto by a rivet 12 and is employed to reduce the hazard to an operator who might come in contact with the box when the fuse is in process of being ruptured.

A circuit is shown diagrammatically including a generator 13, one terminal of which is connected to a load 14, the line then continuing to the terminal 5. The other terminal of the generator 13 is connected to the 65 grounded terminal 15 of the fuse 1.

When an overload occurs in this circuit, the fuse will be ruptured and the overload tube of the fuse structure 1 will be ejected 80 into the arc box 2 along with the gases and the hot particles of the fuse element 4 and the circuit will thus be broken without any danger of the arc being reignited by gases 85 between the fuse terminals or any danger of 90

damaging neighboring apparatus by the ejected material.

The figures of the drawings show the end of the expulsion fuse projecting into the arc box. Tests have shown that this is not always necessary, as my invention operates successfully under certain conditions when the end of the fuse is outside the box but so positioned adjacent thereto, so that all of the ejected material is directed to within the box.

It will thus be seen that I have constructed a safety arc box for fuses that is not deteriorated by the arc because of its metal construction; that is also considerably cheaper than the arc boxes of insulating material such as have been constructed in the past. The method of mounting the fuse so that the materials are projected into the arc box is novel in providing a partition through which the fuse or the materials pass and which prevents the egress of gas, thereby preventing the formation of an ionized path between the terminals such as would cause the arc to re-strike. By the employment of the gauze screen over the end of the arc box adjacent the expulsion end of the fuse, the gases evolved when the fuse blows are permitted to escape under such conditions as to be deionized.

I do not wish to be limited to the particular construction herein shown, as many changes, additions, subtractions or substitutions may be made without departing from the spirit of the invention. I, therefore, do not wish my invention to be limited to any structure except as set forth in the appended claims.

I claim as my invention:

1. In combination, an arc box, an expulsion fuse therefor, said arc box being constructed of metal and having an insulating portion adjacent the expulsion end of the fuse.

2. In combination, a metal arc box, an expulsion fuse therefor, the expulsion end of the fuse extending within the box.

3. An arc box of metal, an expulsion fuse extending within said box; an insulating member in one portion of the box, a terminal on said insulating member connected to the fuse end extending within the box.

4. A metal arc box for an expulsion fuse having the expulsion end of the fuse extending within the box and means for grounding the box.

5. An arc box of metal for an expulsion fuse, an insulating member in one portion of the box having a terminal thereon connected to the fuse end extending within the box and a wire screen covering an opening opposite to the fuse end.

6. An arc box for a fuse constructed of metal and having insulating means associated therewith for supporting one end of the fuse and a wire gauze covering one side of the box.

7. An enclosing chamber for a fuse constructed of metal and having insulating means associated therewith for supporting

the fuse, a wire screen on the side of the box opposite the fuse and means of access to the interior of the box.

8. An arc box of metal having insulating means for supporting a terminal therein, a wire gauze opposite the terminal covering one end of the box and means for grounding the said box.

In testimony whereof, I have hereunto subscribed my name this 17th day of August 1928.

WILLIAM R. TALIAFERRO.
